UNITED STATES PATENT OFFICE.

BRADLEY DEWEY, OF CAMBRIDGE, MASSACHUSETTS, ASSIGNOR TO DEWEY AND ALMY CHEMICAL COMPANY, OF CAMBRIDGE, MASSACHUSETTS, A CORPORATION OF MASSACHUSETTS.

DRIER.

Application filed February 17, 1925. Serial No. 9,824.

To all whom it may concern:

Be it known that I, BRADLEY DEWEY, a citizen of the United States of America, and resident of Cambridge, in the county of Middlesex and State of Massachusetts, have invented new and useful Improvements in Driers, of which the following is a specification.

This invention relates to driers and especially to driers adapted to dry can ends and other disk-like objects which have been coated with a sealing medium or compound in a liquid or semi-liquid state which it is desired to dry completely or partially.

10 Objects of the invention are to provide a drier of the above type which is automatic in its performance and may be operated continuously with minimum cost, the articles being fed to the drier in any suitable or preferred manner; to provide a drier which occupies a minimum amount of space and which efficiently performs its functions with a minimum amount of trouble and attention; and to provide a drier having the new and improved features of construction and arrangement hereinafter described.

15

The invention is shown by way of illustration in the accompanying drawings in which:

30 Fig. 1 is a vertical sectional elevation of the drier; and

Fig. 2 is a view of the top of the drier partly in plan and partly in section on the line 2—2 of Fig. 1.

35 Fig. 3 is a vertical sectional elevation of a modified form of drier, adapted to receive the covers at the bottom and to deliver them at the top, and Fig. 4 is a plan view of the same with parts broken away.

40 In the embodiment of the invention illustrated the drier comprises an upright, hollow inner supporting cylinder 1 having hollow annular extensions 2 and 3 respectively, and surrounding the extensions 2 and 3 are circular plates 4 and 5 respectively which close the opposite ends of the drier chamber, the tubular extension 3 being supported in any suitable manner as by the sleeve-like support 6. Surrounding the cylinder 1 and enclosing

45 the drying chamber is a removable casing 7

which may be attached to the closure plates 4 and 5 as by screw 8, thus enabling the casing to be readily removed for inspecting the inside of the drier for cleaning or other purposes. Suitably secured to the outer periphery of the cylinder 1 is a spiral track 9 which may be of angle iron and which spirals around the outer surface of the cylinder from the upper portion thereof to the lower portion. Extending above and in parallel 60 relationship of the spiral of the track 9 is a helically coiled guide 10 which may be of steel and is circular in cross section. The upper end of the guide being suitably secured to the plate 4 and the lower end being 65 secured to the plate 5.

The disk-like can ends A which have been previously lined with a liquid or semi-liquid lining compound may be introduced into the drying chamber in any suitable manner such as for example by a slide or chute 11 extending through a slot 12 in the casing 7 and a slight distance into the drying chamber. It will at once be apparent that the can ends admitted to the drying chamber assume an angular position, the inner edges thereof engaging the track 9 and the outer portions thereof loosely bearing against the guide 10. A distinct advantage of such construction and arrangement is that can ends of different 70 diameters may be accommodated in the drying chamber without the necessity of changing the relative location of the component parts of the mechanism or replacing one or more of the parts when it is desired to employ the mechanism for a can end of different 75 diameter.

The can ends are caused to travel through the drying chamber from one end thereof to the other and for this purpose a disk 13 is 80 journaled on the cylinder extension 2, a similar disk 14 being journaled on the cylinder extension 3, and the disks 13 and 14 being connected by rods 15 secured respectively thereto in any suitable manner. Fixed to 85 the disk 13 is a worm wheel 16 with which a gear 17 meshes, the gear 17 being driven from any suitable source of power as an electric motor.

It will thus be seen by driving the gear 17 100

the disks 13 and 14 are conjointly rotated and the rods 15, engaging an edge of the can ends A and continuously propel them through the drying chamber guided by the track 9 and guide 10 from the upper portion of the drying chamber to the lower portion thereof where they are discharged through an opening 18 in the lower closure plate 5 and fall upon a slide or chute 19 from which 10 they may be conveyed to any desired place.

The drying chamber may be heated by any suitable means and as shown a burner 20 extends into the tubular extension 3 and slots 21 in the cylinder 1 permits the heated air to 15 pass into the drying chamber and thus accelerate the evaporation of the liquid component in the lining compound previously distributed over the can ends. A modified 20 form of drier is shown by Fig. 3 in which like numerals refer to like parts, but distinguishes from the drier shown in Fig. 1, in 25 that the covers are introduced at the bottom through chute 22 and withdrawn at the top through opening 23. To this end the inner 30 guide member in its upper cycle as at 24 rises to a level and preferably slightly above the outer guide (or the outer guide is made horizontal and thus lower than the inner 35 guide) whereupon the cover slides over the outer guide member and is received by the chute 26 and between longitudinal guides 27 thereon.

An outstanding characteristic of the invention resides in the fact that a drier constructed in accordance with the invention is 35 capable of accommodating can ends of different sizes without change of parts. Another advantage consists in imparting 40 positive rolling motion to the can ends through the drying chamber, this rolling motion bringing all parts of the lining compound into contact with the heated air in the drying chamber thus insuring more uniform 45 and speedier evaporation of the liquid component of the sealing material. Another feature of the invention consists in the relatively 50 easy accessibility of the parts for cleaning or other purposes.

Although I have shown and described a 55 construction which is the best known to me at the present time it will be understood that numerous changes in detail of construction and arrangement may be effected without departing from the spirit of the invention especially as defined in the appending claims. For example, the operation heretofore 60 described may be reversed with minor changes in construction with equally beneficial results.

I claim:

1. A drier comprising a vertically disposed drying chamber having means to admit can ends thereto, spiral means for supporting can ends at an angle in such a manner that the inner edges thereof are guided

and the outer portions thereof are loosely supported, and means independent of said last means to cause the can ends to travel through said chamber.

2. A drier comprising a vertically disposed drying chamber having means to admit can ends thereto, a plurality of helical members constructed and arranged to support can ends at angle in such a manner that the inner edges thereof are guided and the outer portions thereof are loosely supported, and means to roll the can ends along said supporting means through the chamber.

3. A drier comprising a drying chamber having means for admitting can ends thereto, spiral means loosely to support can ends at an angle, and means to cause the can ends to travel through said chamber.

4. A drier comprising a drying chamber having means for admitting can ends thereto, means to heat said chamber, spiral means loosely to support can ends at an angle, said last means being constructed and arranged to accommodate different sized can ends, and means to roll said ends along said supporting means through the drying chamber.

5. A drier comprising a vertically disposed drying chamber having means for admitting can ends thereto, a spiral track in said chamber, means extending above and in parallel relationship to said track whereby the can ends may be supported with one edge thereof engaging said track and an outer portion thereof loosely bearing against said last means, and means to engage said ends and cause them to roll along said track through the drying chamber.

6. A drier comprising a vertically disposed annular drying chamber having means for admitting can ends thereto, means to heat the interior of said chamber, a spiral track within the chamber, a guide extending above and in parallel relationship to said track whereby the can covers may be supported at an angle with one edge thereof engaging said track and an outer portion thereof loosely bearing against said guide, and driving means to cause the can ends to travel with a curvilinear motion from one end to the other of the chamber.

7. A drier comprising a vertically disposed annular drying chamber having means for admitting can ends thereto, a removable casing for said chamber, a spiral track in said chamber, a wire guide extending above and in parallel relationship to said track thereby to support can ends at an angle with one edge thereof resting in said track, said track and guide being constructed and arranged to accomodate can ends of different sizes, and driving means to roll said ends along said track and guide through the drying chamber.

8. A drier comprising a vertically disposed, annular drying chamber having

means for admitting can ends thereto, a removable casing for said chamber, a spiral track in said chamber, a wire guide extending above and in parallel relationship to said track thereby to support can ends at an angle with one edge thereof resting in said track, said track and guide being constructed and arranged to accomodate can ends of different sizes, and driving means to roll said ends along said track and guide through the drying chamber.

Signed by me at Cambridge, Massachusetts, this 11th day of February, 1925.

BRADLEY DEWEY.
